Primary Examiner — Mimosa De(74) *Attorney, Agent, or Firm* — RatnerPrestia(57) **CLAIM**

The ornamental design for a vehicle seat, as shown and described.

DESCRIPTION

FIG. 1 is a front and right side perspective view of a vehicle seat;

FIG. 2 is a front and left side perspective view thereof;

FIG. 3 is a rear and right side perspective view thereof;

FIG. 4 is a front elevation view thereof;

FIG. 5 is a rear elevation view thereof;

FIG. 6 is an elevation view thereof from the left side;

FIG. 7 is an elevation view thereof from the right side; and,

FIG. 8 is a top plan view thereof.

The features of the vehicle seat that are shown in broken lines are for illustration only and form no part of the claimed design.
